UNITED STATES PATENT OFFICE

GIUSEPPE M. BELLANCA, OF NEW CASTLE, DELAWARE

WING STRUCTURE

Application filed June 12, 1931. Serial No. 544,011.

This invention relates to improvements in wing structures.

In the usual type of wing which is provided with a fabric covering a strip of plywood is provided at the entering edge of the wing so as to give a positive curvature at the leading edge of the wing and insure a definite form to the cloth or fabric covering. But little attention has been paid to the joint 10 formed by this veneer or nose box and the ribs of the wing. In operation of the wing the area of the greatest reduced pressure is relatively close to the leading edge of the wing. During flying the fabric covering is 15 therefore subjected to alternations of pressure and tends to move slightly relatively to its supporting structure, namely the ribs of the wing. In this type of wing structure, therefore, is a danger of fracture of the wing 20 fabric due to its forced imposition upon a relatively sharp edge or termination of the nose box or veneer at the entering edge.

A major object of the present invention is to provide an improved type of entering edge 25 structure for an airplane wing.

Another object is to provide an improved metal wing.

Yet a further object is to provide a wing structure having a fabric covering which 30 is positively conformed, at the leading edge, and in which the danger of cutting the fabric is minimized.

With these and other equally important objects in view the invention comprehends 35 the provision of a wing, preferably of metal, which at its entering or leading edge is provided with a nose piece of a stiff relatively inflexible material and which nose piece is of a special curvature so as to minimize danger 40 of rupture of the wing fabric. In order to enable a more ready comprehension of the invention, a preferred modification is shown in the accompanying drawings, in which:

Figure 1 is a perspective view of a portion 45 of a metal wing and associated nose piece.

Fig. 2 is a side elevation of the device shown in Fig. 1.

In accordance with the present invention 50 a wing is provided which preferably comprises metal spars, ribs and truss members.

As shown in the accompanying drawings, the wing preferably comprises tubular metal ribs 1 which are strengthened and rigidified by the tubular metal trusses 2. The tubular metal ribs 1 are shown for only the forward portion of the wing, but it is to be clearly understood that the ribs extend rearwardly to also form the rearward portion of the wing. As shown in the drawings, the wing is of the full-truss diagonal type, although 55 it is to be understood that other forms of wings, such as semi-truss or full-truss, diagonal and vertical, may be employed. Likewise it will be understood that if desired the invention may include the use of diagonal bracing tubes in a manner well understood by those skilled in the art. 60

Any metal having the desired characteristics of a high ratio of strength to weight 65 may be employed. Preferable types of metals are the light weight ferrous alloys of the duralumin type. The wing is provided with front and rear spars, only the front spar being shown in the drawings. The spars may preferably comprise two longitudinally extending tubular members 3 which are integrally joined to an intermediate web 4, of any desired configuration. The tubes 3 and 4 may be integrally joined together by an autogenous weld. The ribs 1 are preferably welded 70 to the front spar, as shown clearly in Fig. 2. This type of structure forms, as is known, 75 a very satisfactory strong and rigid wing skeleton.

Associated with the wing is the nose piece 80 7. This may be of ply-wood but preferably is composed of a sheet of dural or other light weight metal. As shown in Figures 1 and 2, this nose piece abuts the forward ends of the ribs 1 and extends rearwardly of the leading 85 or entering edge a substantial distance on the upper and lower surfaces of the wing. At the leading edge the nose piece is a substantially continuous surface. Near its terminations at the upper and lower surfaces the nose 90 piece is cut out, at 9, as clearly shown in Fig. 1, so as to permit the ends of the nose piece to extend below the surface of the ribs 1. 95

In order to maintain the nose piece 7 in a fixed position relative to the wing frame, the 100

longitudinal metallic tubes 5 and 6 are provided. While these are shown as of solid construction they obviously may be hollow tubular members. The ends of the nose piece are secured to the rods 5 and 6 in any desired manner. In the preferred form of the invention each end 8 of the nose piece is curved about the rods 5 and 6. If desired, the curved portion 8 of the nose piece may be welded to the bars 5 and 6 at any desired point. The rod members 5 and 6 may be rigidly secured to the ribs 1 by welding.

It will be seen from this description that the nose piece 7 forms a rigid entering edge of the wing and that when the fabric is applied to the wing, in the usual manner, a definite form is given to the cloth at the entering edge. However, unlike prior structures, the edge or termination of the nose piece does not contact with the fabric. The nose piece adjacent its ends is given a shorter radius of curvature than its adjacent flatter sections so that the fabric, even under maximum flexure, will not contact with a sharp edge. This is done, as clearly shown in Fig. 2, by so-to-speak depressing the ends of the nose piece considerably below the contour of the wing, as defined by the upper surface of the ribs 1. Therefore, when the wing fabric flexes due to variations in pressure thereon, such flexure will occur in the area adjacent the termination of the nose piece, but under the most severe conditions of flexure the fabric will not encounter a sharp edge of a subjacent surface. In operation, therefore, the wing fabric always abuts a substantially flat surface which presents no cutting or fraying.

While a preferred embodiment of the invention has been shown and described, it is to be understood that this is given merely as exemplary of the principles of the invention, and since this may be embodied in other specific forms of structures it is not intended to be limited to that shown and described except as such limitations are clearly imposed by the appended claims.

I claim:

1. A wing structure comprising a spar positioned adjacent the leading edge of a wing, ribs associated with the spar, a nose piece of rigid material positioned at the leading edge of the wing and extending an appreciable distance rearwardly on the upper and lower surface of the wing, the nose piece being depressed adjacent its termination so as to assume a position spaced inwardly from the wing ribs.

2. A wing structure comprising a leading spar and associated ribs composed of a light weight high strength metal, a metallic nose piece forming the entering edge of the wing, the nose piece being positioned above the ribs at the entering edge, and being positioned below the ribs near its terminations.

3. A wing structure comprising a wing hav-

ing suitable spars and ribs, a nose piece for the wing, a portion of the nose piece projecting outwardly of the ribs and another portion being spaced inwardly of the ribs.

4. A wing structure comprising a longitudinal leading spar and associated ribs, a nose piece of rigid material supported on the outer surfaces of the ribs and having a part projecting inwardly of the ribs, and a fabric covering attached to the wing.

5. A wing structure comprising metal spars and ribs, a metal nose piece supported at the leading edge of the wing on the outer surfaces of the ribs and terminating rearwardly of the leading edge, the terminations of the nose piece being depressed below the exterior contour of the wing as defined by the ribs.

6. A wing structure comprising metal spars and ribs, a metal nose piece supported at the leading edge of the wing on the outer surfaces of the ribs and terminating rearwardly of the leading edge, the terminations of the nose piece being depressed below the exterior contour of the wing as defined by the ribs, and a fabric covering overlying the nose piece and ribs.

7. A wing structure comprising spars and ribs of tubular formation welded together, a sheet metal nose piece attached to the leading edge of the wing and supported by the ribs, the ends of the nose piece extending inwardly of the ribs, a longitudinal member supporting each of the terminal ends of the nose piece, the longitudinal members being secured to the underside of the ribs.

8. A wing structure comprising spars and ribs of tubular formation welded together, a sheet metal nose piece attached to the leading edge of the wing and supported by the ribs, the ends of the nose piece extending inwardly of the ribs, a longitudinal member supporting each of the terminal ends of the nose piece, the longitudinal members being secured to the underside of the ribs, and a fabric cover overlying the nose piece and ribs.

In testimony whereof I affix my signature.

GIUSEPPE M. BELLANCA.
